UNITED STATES PATENT OFFICE

162,158

BOOT OR SIMILAR ARTICLE

John E. Hard, Edgewood, R. I., assignor to Bristol Manufacturing Corporation, Bristol, R. I., a corporation of Rhode Island

Application October 21, 1950, Serial No. 12,650

Term of patent 14 years

(Cl. D7—7)

To all whom it may concern:

Be it known that I, John E. Hard, a citizen of the United States of America and residing at Edgewood, Rhode Island, have invented a new, original, and ornamental Design for Boot or Similar Article, of which the following is a specification, reference being had to the accompanying drawings, forming a part thereof, wherein:

Fig. 1 is a side elevational view of the outer side of a boot showing my new design, the opposite inner side of which is devoid of decoration.

Fig. 2 is a rear elevation of the boot; and

Fig. 3 is a front elevation of the boot.

I claim:

The ornamental design for a boot or similar article, substantially as shown and described.

JOHN E. HARD.
